CLAIM

The ornamental design for a grab bar, as shown and described.

DESCRIPTION

FIG. 1 is a right perspective view of the grab bar showing my new design;

FIG. 2 is a left perspective view of the grab bar of FIG. 1;

FIG. 3 is a front view of the grab bar of FIG. 1;

FIG. 4 is a rear view of the grab bar of FIG. 1;

FIG. 5 is a top view of the grab bar of FIG. 1;

FIG. 6 is a bottom view of the grab bar of FIG. 1;

FIG. 7 is a left side view of the grab bar of FIG. 1;

FIG. 8 is a right side view of the grab bar of FIG. 1;

FIG. 9 is a side sectional view of the grab bar indicated at plane 9 of FIG. 1;

FIG. 10 is a front sectional view of the grab bar indicated at plane 10 of FIG. 1;

FIG. 11 is a right perspective view of the grab bar of FIG. 1 showing environmental structure;

FIG. 12 is a left perspective view of the grab bar of FIG. 11;

FIG. 13 is a front view of the grab bar of FIG. 11;

FIG. 14 is a rear view of the grab bar of FIG. 11;

FIG. 15 is a top view of the grab bar of FIG. 11;

FIG. 16 is a bottom view of the grab bar of FIG. 11;

FIG. 17 is a left side view of the grab bar of FIG. 11;

FIG. 18 is a right side view of the grab bar of FIG. 11;

FIG. 19 is a side sectional view of the grab bar indicated at plane 19 of FIG. 11; and,

FIG. 20 is a front sectional view of the grab bar indicated at plane 20 of FIG. 11.

In FIGS. 1-20, broken lines indicate environmental structure that forms no part of the claimed design.

1 Claim, 20 Drawing Sheets
